UNITED STATES PATENT OFFICE

JOHN M. SNYDER, OF FAIRFIELD, ILLINOIS

STOVE CLOSURE

Application filed January 24, 1930. Serial No. 423,107.

This invention relates to an improved temporary removable closure for use in association with door frames of various types of stoves, furnaces, boilers, and the like.

5 The invention has more specific reference to a simple and economical closure in the nature of a guard or shield, which is intended to be placed on the door frame during the night so that the door may be left open, so 10 that an appropriate draft may be secured, and so that the combustible materials in the fire chamber will be prevented from falling out through the door opening.

Briefly stated, the invention is predicated 15 upon a closure appliance including a plate having a screened opening therein, together with suitably constructed and conveniently operated retaining means for maintaining the closure in the doorframe overnight, or at 20 any other time desired.

In the drawings:

Figure 1 is an elevational view showing a conventional stove with the appliance in place.

25 Figure 2 is an inside elevational view of the appliance.

Figure 3 is an edge view showing the arcuate configuration.

Figure 4 is a cross section on the line 4—4 30 of Figure 2.

Figure 5 is a similar sectional view on the line 5—5 of Figure 2.

In the drawings, in Figure 1, the stove is generally represented by the reference character 6, the door frame at 7, and the door 8. The improved closure or guard appliance is generally represented by the reference character 9.

As before stated, the appliance comprises a metal plate, whose imperforate or solid portion is indicated by the numeral 10. The lower portion is formed with a rectangular hole in which a closing screen 11 is arranged. The appliance is of general arcuate configuration and rectangular outline, but may vary in form to permit it to be adapted to different kinds and shapes of door openings in furnaces, stoves, and equivalent heating apparatus.

At about the center of the closure, I pro-

vide a turn button, including a stem or shaft portion 12, and an operating knob 13. The stem is rotatable in a suitable bearing hole formed on the plate, and on the inner end thereof is a cross head 14 which forms a connection between a pair of retaining links 15 which function as latches. The inner ends of these are pivotally connected to the opposite ends of the cross heads 15 and the outer ends extend through and beyond guide keepers 16.

The reference character 17 designates a tensioning and retaining spring for the turnbutton and numerals 18 represent stops for the link members 15.

In practice the closure is placed in position on the doorframe, as seen in Figure 1, at which time the turnbutton is arranged to project the free end portions of the latches 15 into the rim or surrounding edge portion of the doorframe. This holds the appliance in position, and allows the door 8 to be swung open. When the appliance is thus in place, it affords sufficient draft and prevents the coal or wood from falling out. It is therefore, a safety appliance and functions as a remarkable fuel saving device.

A careful consideration of the drawings in connection with the description will enable the reader to obtain a clear understanding of the invention and features. Therefore, a more lengthy description is regarded as unnecessary. Minor changes in shape, size, and rearrangement of parts may be resorted to in actual practice if desired.

I claim:

A removable closure for a stove opening comprising a plate including a solid portion and an opening, a screen covering the opening, said solid portion restricting the opening of the stove, a pair of latch members 90 slidably arranged on the inner face of the plate engaging the inner walls of the stove opening when the plate is placed in said opening and an operating member passing through the solid portion of the plate and 95 connected with the latch members for projecting and retracting the same.

In testimony whereof I affix my signature.

JOHN M. SNYDER.
